United States Patent Office

Des. 231,171
Patented Apr. 9, 1974

231,171

DRESSER FRONT

Huey T. Keller, 1609 Davidson Road,
High Point, N.C. 27260

Continuation-in-part of abandoned design application Ser.
No. 24,705, Aug. 26, 1970. This application Oct. 11,
1972, Ser. No. 296,620

Term of patent 14 years

Int. Cl. D6—04

U.S. Cl. D6—164

FIG. 1

FIG 2

FIG. 1 is a front plan view of a dresser or the like, showing my new design:

FIG. 2 is a top plan view of such design, and

FIG. 3 is an end elevational view of the same.

This application is a continuation-in-part of my co-pending application Ser. No. D 24,705 filed Aug. 26, 1970 and now abandoned.

I claim:

The ornamental design for a dresser front, as shown and described.
